UNITED STATES PATENT OFFICE

WALTER M. SCHWARTZ AND HARRY COULSTON, OF PHILADELPHIA, PENNSYLVANIA,
ASSIGNORS TO THE PHILADELPHIA TEXTILE MACHINERY COMPANY, OF PHILADELPHIA, PENNSYLVANIA, A CORPORATION OF PENNSYLVANIA.

MACHINE FOR DRYING HOSIERY.

1,062,510.

Specification of Letters Patent.

Patented May 20, 1913.

Application filed August 14, 1912. Serial No. 715,058.

To all whom it may concern:

Be it known that we, WALTER M. SCHWARTZ and HARRY COULSTON, citizens of the United States, and residents of Philadelphia, Pennsylvania, have invented certain Improvements in Machines for Drying Hosiery, of which the following is a specification.

The object of our invention is to construct a machine for thoroughly and quickly drying hosiery.

The machine consists essentially of a drying chamber; a series of forms on which stockings to be dried are placed; and means for conveying the forms so as to cause them to travel into and through the drying chamber and out again; the rate of travel of the forms being such that the operator has time to place a dampened stocking on each form, as it passes, and to remove a dried stocking; the operation of the machine allowing for the rapid and successful accomplishment of the work for which it is intended.

In the drawings, we have illustrated a machine having four tables and four independent driers, so that four operators place the stockings on the forms; two operators removing the stockings from the forms.

It will be understood that while we have illustrated a machine of this type, a machine having a single drying chamber and a single table may be used without departing from the essential features of the invention.

In the accompanying drawings:—Figure 1, is a perspective view of our improved hosiery drier; illustrating our invention; Fig. 2, is a vertical sectional view on the line 2—2, Fig. 1; illustrating the drying chambers and the means for circulating the heated air through the chambers; Fig. 3, is a plan view; Fig. 4, is a plan view of one section of the drier showing the forms in position and the drier casing removed; Fig. 5, is a plan view showing the cams for feeding the carriers, on which the stocking forms are mounted, over the table and through the drying chamber; Fig. 6, is a transverse sectional view on the line 6—6, Fig. 4; Fig. 7, is an enlarged sectional view on the line 7—7, Fig. 4, showing a carrier and a portion of one of the stocking forms; Fig. 8, is a side view of the carrier illustrated in Fig. 6; Fig. 9, is a sectional plan view on the line 9—9, Fig. 8; Fig. 10, is an inverted plan

view of the carrier illustrated in Fig. 7; and Fig. 11, is a plan view of a modification of the table and drying chamber.

Referring to the drawings, 1 is the base of the machine mounted, in the present instance, on legs 2. This base is shaped, as clearly shown in Fig. 3, and has four tables, two on each side of the machine; the tables on each side being spaced apart forming recesses 5 for the operators who remove the stockings from the stocking forms.

Projecting upwardly from the base is a drying chamber 6, made as clearly shown in Fig. 1; having four compartments 7, one for each table 4. The face of each compartment is inclined as shown, and the central portion is vertical so as to increase the space for the operators above mentioned. In the central portion 8 of the drying chamber 6 is a vertical partition 9 which divides the drying chamber into two sections, and in each section there is a steam coil 10 for heating the air which is circulated through the drying compartments.

11 is a horizontal shaft having bearings 12 mounted in the frame of the machine and driven from the main driving mechanism. On this shaft 11 are fans 13 which are located in openings in the vertical partitions 14 so that the air circulates past the steam coils and through each section of the drying chamber; thoroughly drying the stockings which pass therethrough.

The drying chamber is made of a frame open on all sides and in order to close the frame there are end plates 15 held to the frame by suitable clamps and side plates 16 also held by clamps and having slots 17 therein for the passage of the stocking forms into and out the machine. The heating section of the drying chamber is closed by plates 18, as clearly shown in Fig. 1. This construction may be modified, however, and some of the plates may be permanently fastened in position, but we prefer to make them detachable so that in case of needed repairs, access may be readily had to the interior of the heating chamber. On each side of the slots 18 are mounted guides 19 for directing the stocking forms into the slots. By providing narrow slots, very little heated air escapes from the heating chamber.

In the base of each table 4 are four shafts

20, 21, 22, and 23, adapted to suitable bearings 24, Fig. 5. On the shaft 20 is a gear wheel 25, which meshes with a gear on the driven shaft 26. Also on the shaft 20 are 5 beveled gear wheels 27, which mesh with beveled gear wheels 28 on the shafts 21 and 23 and on the opposite end of each of these shafts is a beveled wheel 29 which, in turn, meshes with a bevel wheel 30 on the shaft 10 22, so that all of the shafts turn in unison.

Secured to the shaft 20 are brackets 31 to which is secured the scroll cam 32 in the form of a ribbon. This cam acts to feed the carriers for the stocking forms forward 15 across the front of the table and while the forms are being traversed by this cam, the operator (or operators) places the stockings on the different stocking forms.

33 is a scroll cam secured to the shaft 21 20 and made in the same manner as the cam 32. This cam feeds the carrier into the drying chamber. 34 is a scroll cam on the shaft 22, which feeds the carriers across the drying chamber and 35 is a scroll cam on the shaft 25 23 for feeding the carriers out of the drying chamber and into position for the operator to remove the dried stockings from the stocking forms.

It will be noticed that both the cams 33 30 and 35 stop some distance from the cam 34 and there is a short cam 36 on the shaft 33 at the delivery end of the cam 34. By this means we are enabled to cause the carriers to dwell for a given length of time in the 35 drying chamber so that while there is practically a continuous movement of all of the carriers, a certain number of carriers remain stationary for a predetermined length of time within the drying chamber, consequently, there are more carriers and stocking forms within the chamber at all times than there are outside; giving ample time for the stockings to become thoroughly dried, yet allowing for the continuous movement of the carriers while one stocking is 45 being removed from the form and another placed thereon.

The ends of the cams which are located at right angles to each other are so formed 50 that as one cam delivers a carrier to a certain point another cam removes the carrier laterally from the position; one cam, however, holding the carrier until the other cam has properly engaged it so that the carriers are at all times under the control of the cams.

In the present instance, the delivery end 55 of each cam has a reduced projection 37 at right angles to the center line of the cam, while at the opposite end is a tapered point 38, which passes the projection 37 at the delivery end of each cam so that the carriers are traversed and fed in a direction at right angles to their previous movement.

65 39—39, are the carriers made as clearly

shown in Figs. 6 to 10 inclusive. Each carrier has a base 40 from which projects a stud 41 having a roller 42 which is engaged by the several cams 32 to 36 respectively. The base 40 of each carrier travels in guide- 70 ways 43, 44, 45 and 46 in the table 4, as clearly shown in Fig. 4 and, as before remarked, the cam 32 traverses the carriers across the front of the table. The cam 33 feeds the carriers longitudinally into the 75 drying chamber; allowing them to accumulate, as illustrated in Fig. 4, and as one carrier pushes another forward the cam 34 engages a carrier and moves it laterally in the slot 45 across the drying chamber; the 80 cam 36 engaging the carriers and moving them longitudinally toward the outlet opening; the carriers accumulating in the slot 46 and as one carrier pushes another one forward it is engaged by the cam 35 and moved 85 out of the heating chamber and into the path of the cam 32.

While the carriers are traversing the slots outside of the drying chamber, as before remarked, there is sufficient time for one 90 stocking to be removed from the stocking forms and another placed thereon; the drying process being repeated over and over again.

On each carrier 39 is an inclined project- 95 ing bracket 47, Figs. 7 and 8, and pivotally mounted on this bracket is a cylindrical block 48 having a projecting rib 49 to which the stocking form or board 50 is secured, in the present instance, by screws 51. This 100 stocking form is given an inclined position, as clearly illustrated in Figs. 1, 4, and 8, which allows the operator to more readily place a stocking on its form, prior to being traversed through the heating chamber. 105

By swiveling the stocking form on the carrier, the form can be presented sidewise to the operator, who places the stocking on the form, as it has been found that a stocking can be more readily and accurately 110 placed on a form, when the form is in this slanting position; all portions of the stocking being properly stretched over the form.

On the rotating block 48 are two wings 52 and 53 and on the under side of the carrier is a slotted projection 54. After the stockings are dried and before they are forced out of the slot 17 in the casing, the forms must be turned so as to be presented to the slot on edge and this is accomplished 120 by a disk 55 located within the drier in position to contact with the lower portion of the stocking form 50; causing the stocking form to turn at right angles and thus allowing it to pass through the narrow slot 125 17 in the casing. In order to present the stocking form sidewise to the operator, we secure a lug 56 on the fixed guide of the table which contacts with the wing 53 of the block 48 and as each carrier moves past 130

this lug, the lug turns the different stocking forms at right angles, as illustrated in Fig. 4. There is no change in the position of the form as the carrier travels across the table until it reaches a point in front of the other slot 17 of the casing, when it is again turned at right angles by the slotted lug 54 on the under side of the block 48 engaging the beveled end of the guide 57; which turns the stocking form so that it will be presented toe forward to the slot 17 and after it passes through the slot and is within the drying chamber it is again turned at right angles by a projection 58, which is engaged by the wing 52 on the block 48; remaining in this position until it is again turned at right angles by the wheel 55, as described above. By this arrangement not only are the forms so turned that they can pass through a very narrow slot in a casing of the heating chamber, but they are presented in the best position to the operator to place a stocking thereon and the forms are so arranged in the drying chamber that a number of them can be located side by side, (while in the chamber) allowing a large number of stockings to remain in the drying chamber; thus facilitating the process of drying.

In order to limit the movement of the block 48 which carries the stocking form 50 when it is turned by the projections coming in contact with the wings or lugs on the head, stops 58 are formed on the bracket 47 which are in the path of a projection 59 on the said head 48; thus insuring the proper alignment of the stocking forms with the slots in the casing of the drying chamber.

In the present instance, the shaft 11 is the driving shaft having a pulley 60 for the power belt and on the opposite end of the shaft is a pulley 61 around which passes a belt 62 to a pulley 63 on a shaft 64 mounted in suitable bearings 65 and, in the present instance, there is a reducing gear in the gear box 66 which is between the shaft 64 and the pulley 63, but this construction may be dispensed with in some instances without departing from the essential features of the invention.

On the shaft 64, in the present instance, are chain wheels 67 and chains 68 pass around these chain wheels and around chain wheels 69 on shafts located within a change gear box 70. The shaft on which the chain wheels 69 are mounted is geared to the shaft 26 carrying the gear wheel, which meshes with the gear wheel 25 on the cam shaft 20 above described.

A machine of the above described type 60 consists substantially of four units, but it will be understood that a single unit machine may be employed; said single unit machine having but one table, or a two unit machine, having two tables, may be used, 65 (Fig. 11) or one having more than four

tables may be constructed, without departing from the spirit of the invention.

Thus it will be seen that we provide a series of movable carriers on which the stocking forms are mounted; means being 70 also provided whereby they are brought in front of an operator so that a stocking may be properly placed upon a form. When the stocking has been properly placed in the desired position, the form is turned and 75 allowed to pass through a narrow slot in the drying chamber; the forms collecting and remaining in the drying chamber a sufficient length of time to allow the dampened stockings to be thoroughly dried. The forms are 80 then turned and forced out another narrow slot in the drying chamber and brought in position for the operator to remove the dried stocking.

We preferably speed the machine so that 85 only two operators are required; one operator placing stockings on the stocking forms and another removing the dried stockings from the forms, but it will be understood that in some instances the machines may 90 be driven at such a speed as to allow one operator to perform the work.

While our invention is intended primarily for a stocking drying machine; a singeing device may be used in connection with the 95 drier to singe stockings while they are on the forms and the feeding mechanism for the carriers and stocking forms may be used in connection with a machine for singeing, where the singeing is a separate operation. 100

In Fig. 11, we have illustrated a modification of our improved drier, in which there is a central drying chamber 6^a longitudinally arranged. An operator's table 4^a is located on each side thereof and the conveyers travel in a quadrangular guideway; traveling across the table and allowing time for the operator to adjust the stockings onto the form. The carriers then traverse the short way into the drying chamber and then travel 110 slowly within the chamber and discharge at the opposite end. By this construction it is not necessary to turn the forms prior to their leaving the drying chamber and an operator may remove the dried stocking 115 from the form at the delivery end of the machine, or means may be provided for automatically gripping the stocking and removing it from the board. This particular construction will form the subject of a separate 120 application.

In the construction above noted the heating pipes are located between the two lines of carriers within the heating chamber and the circulating fan or fans are mounted on 125 a longitudinal shaft for properly circulating the air within the chamber.

It will be noticed, both in the main figures and the modification, that when the carriers are traveling over the exposed table the 130

hosiery form is free to be rotated by the operator, so that the operator can properly place the stockings on the form and examine both the front and the back of the board, insuring the proper arrangement of the stocking on the form. The operator can leave the form in any position desired and mechanism will automatically turn the form so that it will enter the slot in the casing on end.

10. We claim:

1. The combination in a hosiery drier, of a drying chamber; a series of detached carriers; a hosiery form mounted on each carrier; and means for traversing the said forms into and through the drying chamber.

15. 2. The combination in a hosiery drier, of a table; a drying chamber; detached carriers; a hosiery form mounted on each carrier; and means for traversing the carriers

20. over the table and through the drying chamber.

25. 3. The combination in a hosiery drier, of a drying chamber, a table; an endless guide extending over the table and into the drying chamber; and a series of detached carriers each having a stocking form thereon and adapted to travel on the guide; with means for traversing the carriers.

30. 4. The combination in a hosiery drier, of a table; a casing inclosing the drying chamber; an endless guide on the table extending into the drying chamber; the front of the casing having two vertical slots alining with the guide; with a series of carriers each having a stocking form thereon; and means for traversing the carriers on the guide so that the stocking forms will pass from the table through one slot and into the drying chamber and out through the other slot.

35. 5. The combination in a hosiery drier, of a table; a casing inclosing a drying chamber; said table having a quadrangular endless guideway; the casing of the drier having two vertical slots alining with the guideway; a series of carriers adapted to travel

40. in the guideways; each carrier having a hosiery form thereon; with means for traversing the carriers in the quadrangular guideways so that the hosiery forms will 45. pass over the table through one slot in the casing and into and through the drying chamber and out through the other slot.

45. 6. The combination in a hosiery drier, of a table; a drying chamber; a casing inclosing the drying chamber; said table having a guideway extending into and through the drying chamber; a series of carriers; each carrier having a hosiery form; and means, under the table, for imparting motion to the 50. carriers.

55. 7. The combination in a hosiery drier, of a table; a drying chamber; a casing inclosing the drying chamber; said table having an endless guideway extending into and 60. through the drying chamber; a series of carriers;

riars; a hosiery form mounted on each carrier; and cams, under the table, for imparting motion to the carriers.

8. The combination in a hosiery drier, of a table; a drying chamber; a series of carriers adapted to travel on the table and through the drying chamber; means for traversing the said carriers; a hosiery form mounted on each carrier; and means for turning the forms as the carriers are traversed.

75. 9. The combination in a hosiery drier, of a table; a drying chamber; a series of carriers; means for traversing the carriers over the table and through the drying chamber; a head mounted on each carrier; a hosiery form carried by each head; and means for turning the forms as the carriers are traversed.

80. 10. The combination in a hosiery drier, of a table; a casing inclosing a drying chamber and having two slots therein; carriers adapted to travel over the table and through the drying chamber; a hosiery form mounted on each carrier; and means for turning each hosiery form prior to its 85. entering one of the slots in the casing of the drying chamber; with means for traversing the carriers.

85. 11. The combination in a hosiery drier, of a table; a casing inclosing a drying chamber; a series of carriers arranged to travel over the table and through the drying chamber; a hosiery form pivotally mounted on each carrier; said casing having narrow 90. slots for the passage of the hosiery forms; means, in front of one slot, for turning the hosiery forms prior to their passing through the slot; and means, within the drying chamber back of the other slot, for turning the hosiery forms prior to their leaving the heating chamber through the other narrow slot.

95. 12. The combination in a hosiery drier, of a table; a casing inclosing the drying chamber; an endless guideway extending over the table and through the drying chamber; a series of carriers arranged to travel in the guides; means for traversing the said carriers, said casing having narrow 100. vertical slots therein in line with the guides; a hosiery form pivotally mounted on each carrier; and means for turning the hosiery forms prior to their entering or leaving the drying chamber.

105. 13. The combination in a hosiery drier, of a table; a casing inclosing a drying chamber; means for circulating air through the casing; an endless guideway extending over the table and through the casing; said casing having two narrow slots, one alining with each longitudinal run of the guideway; carriers arranged to travel on the guideway; means for traversing the carriers; a hosiery form pivotally mounted on 110. 115. 120. 125. 130.

each carrier; and means for turning the hosiery forms prior to their entering and leaving the drying chamber, so that they can pass through the narrow slots.

5 14. The combination in a hosiery drier, of a table having an endless guideway thereon; a casing inclosing the drying chamber; means for circulating air through the casing; said casing having two narrow slots, 10 one alining with each longitudinal run of the guideway; carriers arranged to travel in the guideway; means for traversing the carriers in an endless path in the guideway; a hosiery form mounted on each carrier; 15 means for turning the hosiery forms prior to their entering and leaving the drying chamber so that they can pass through the narrow slots; and means for again turning the hosiery forms after they leave the drying chamber so as to present them side-on to the operator.

15 16. The combination in a hosiery drier, of a table having a quadrangular guideway therein; a casing extending over a portion 20 of the table and inclosing a drying chamber; a series of carriers arranged to travel in the guideway; independent cams for traversing the carriers transversely and independent cams for traversing the carriers longitudinally; means for gearing the cams so that they will turn in unison; each carrier having a depending portion arranged to be engaged by the cams so that when a carrier completes its movement in 25 one direction, it is engaged by the cam and traversed in a direction at right angles thereto; with a hosiery form mounted on each carrier.

16 17. The combination in a hosiery drier, 40 of a table having a quadrangular guideway therein; a casing inclosing a drying chamber and extending over the table; a series of carriers arranged to travel in the guideway; a hosiery form pivotally mounted on each carrier; longitudinally and transversely arranged cams for traversing the carriers through the guideway—the two longitudinal cams being shorter than the guideway so as to allow the carriers to 45 cumulate in the drying chamber; one carrier pushing another forward until engaged by the traversing cams.

17 18. The combination in a hosiery drier, of a table having a quadrangular endless guideway therein; a casing inclosing a drying chamber and extending over a portion of the table; said casing having two vertical narrow slots; one in line with each longitudinal guideway of the table; with means for circulating heated air through the drying chamber; four shafts under the table; means for driving the shafts in unison; a scroll cam on each shaft; each carrier having a depending portion engaged by the cams; the end of a 65 cam of one shaft overlapping the end of a

cam arranged at an angle thereto, so that each carrier is held by one cam until it is engaged by the other cam.

18. The combination in a hosiery drier, of a table having a quadrangular guideway 70 therein; a drying chamber extending over a portion of the table; a series of carriers; a hosiery form mounted on each carrier; two transverse shafts and two longitudinal shafts under the table; a scroll cam mounted on each transverse shaft and extending substantially the full length of the guideway in the table; a scroll cam on each longitudinal shaft terminating short of the full length of the slot; and a short scroll cam on the delivery side to transfer the carriers from the inner transverse run to the discharge longitudinal run of the guideway.

19. The combination of a table; a guide thereon; a carrier adapted to the guide; 85 means for traversing the carrier; and a hosiery form pivotally mounted on the carrier.

20. The combination of a table; a guide thereon; a carrier adapted to the guide; a slotted casing; a pivotally mounted stocking 90 form on the carrier; and means for holding the said form to allow it to pass through the slot in the casing.

21. The combination of a fixed guide; a carrier adapted to the guide; means for 95 traversing the carrier; an angular bracket on the carrier; a head swiveled in the bracket; and a stocking form mounted in the head.

22. The combination of a carrier; a bracket thereon; a head mounted in the bracket and having a flange; a stocking board secured to the flange; wings on the head; and fixed means with which the wings contact to turn the head.

23. The combination of a guide; a carrier 105 adapted to travel therein having a bracket extending above the guide; a head mounted to turn in the bracket; a stocking form carried by the head; wings on the upper surface of the head; and a grooved projection on the 110 under side of the head, said projection adapted to engage the guide during a portion of the movement of the carrier.

24. The combination in a hosiery drier, of a base frame having four tables; an endless 115 quadrangular guideway on each table; a casing extending over the base and having vertical slots therein; an independent set of carriers for each table; a hosiery form mounted in each carrier; means for traversing the carriers; means for turning the hosiery forms so that they will pass through the slots in the casing to a central heating chamber; and a horizontal fan shaft; with fans thereon for circulating the air through 125 the heating chamber.

25. The combination in a hosiery drier, of a base frame having four tables; an endless quadrangular guideway on each table; a casing extending over the base and having 130

vertical slots therein; an independent set of carriers for each table; a hosiery form mounted in each carrier; means for traversing the carriers; means for turning the hosiery forms so that they will pass through the slots in the casing to a central heating chamber; a horizontal fan shaft; fans thereon for circulating the air through the heating chamber; said tables being spaced apart 5 at the center; the casing of the heating chamber being recessed at the center to allow the operator, who removes the hosiery from

the forms, to stand in the space between the tables while the operator, who places the hosiery on the forms, stands in front of the 15 tables.

In testimony whereof, we have signed our names to this specification, in the presence of two subscribing witnesses.
